DISPLAY RACKS

John D. Maliff, South Boston, Mass., assignor to The Gillette Company, Boston, Mass., a corporation of Delaware

Filed June 11, 1956, Ser. No. 590,439

3 Claims. (Cl. 211—49)

The present invention relates to the displaying of merchandise on retail store counters or at other locations to invite the attention of prospective purchasers to the attractiveness of, and their need for, the goods being displayed. More particularly, the invention concerns improved racks to which merchandise cases may be detachably secured, and in certain respects is particularly pertinent to improved racks to which merchandise cases are detachably secured in stacked relation.

Display racks of the type shown in U.S. Patent No. 2,740,529, to Schladermundt et al., granted April 3, 1956, have proven very effective in promoting the sale of merchandise through advantageous display. The present invention incorporates novel improvements over such a construction, and provides economies thereover. It is to be noted that these racks are intended for use with merchandise display cases having re-entrant surfaces forming vertically extending guideways or grooves. One such merchandise case particularly well adapted for displaying safety razor sets is shown in U.S. Patent No. 2,702,116, to Shnitzler et al., dated February 15, 1955, and for purposes of illustration only, that merchandise case is herein described and illustrated with respect to the various aspects of my rack invention.

It is the principal object of my invention to provide a display rack constituting an improvement on the general type shown in the above-mentioned Schladermundt patent. This improved rack is more economical, not only in its manufacture, but in its storage, shipment and in other respects due to its great simplification, while at the same time the wide range of utility of the earlier construction is retained.

Accordingly, my invention in one of its aspects comprises the provision of a nonself-supporting display rack to which may be detachably secured merchandise cases of the type having re-entrant surfaces forming vertically extending guideways. Mounting edges on the rack enter these guideways to effect securement of the cases thereto, and an abutment disposed near the lower portion of the rack positions a displayed case so that it provides support for the rack in an upright sense. Thus the rack and the displayed cases combine to provide mutual support for each other; the case maintains the rack upright while the rack maintains the cases in stacked relation.

My invention in another of its aspects comprises the provision of a display rack, to which may be secured a supply of merchandise cases in the manner described above, formed with its vertical dimension greatly exceeding by several times at least its shortest base dimension, so that several cases may be attached thereto in stacked relation. Further, this aspect of the invention contemplates a rack which is, at least initially, substantially planar and formed of sheet material. When thus formed, great economies can be realized in shipping and storing display racks.

The invention in a further related aspect comprises the

2

provision of a display rack, for use in association with merchandise cases of the type described above, which is substantially planar before attachment of merchandise cases and which is formed of resilient sheet material. In use, the mounting edges of this rack may be bowed inwardly to facilitate their introduction into the merchandise case guideways. Upon being released these edges will more firmly enter the case guideways under the influence of the resilient characteristics of the rack material, and thereby effectuate more secure attachment of the cases thereto.

My invention in yet another aspect involves the provision of an initially flat display rack formed of fibrous material such as cardboard. Again, the fibrous rack is provided with mounting edges which may be bowed inwardly for insertion into re-entrant merchandise case guideways. The cardboard has sufficient natural resilience so that the side edges will enter the case guideways and securely effectuate attachment therebetween. In racks of this general type it is common practice to slide the display cases therefrom as each case is removed. Normally, it would be expected that a rack formed of a fibrous material would either not be strong enough to serve this purpose, or would possess such high frictional characteristics that the cases could not be readily slid therefrom. However, certain unobvious discoveries have been made and will be described in detail below which enable the successful use of cardboard in accordance with the teachings of my invention.

The above and other objects, features, and aspects of my invention will now be described in greater detail by reference to the accompanying drawings and the novelty thereof, particularly pointed out in the appended claims.

In the drawings:

Fig. 1 is a view, in perspective, of one form of my improved display rack showing merchandise cases attached thereto;

Fig. 2 is a view, in perspective, showing another embodiment incorporating other aspects of my invention and also showing merchandise cases attached thereto;

Fig. 3 is a partial section taken on line 3—3 in Fig. 1;

Fig. 4 is a view, in side elevation, of the display rack shown in Fig. 2, indicating in phantom the method of attachment of a merchandise case thereto;

Fig. 5 is a partial view, in perspective, of the rack shown in Fig. 2, particularly illustrating the manner in which a merchandise case is detached therefrom;

Fig. 6 is a section taken on the line 6—6 in Fig. 4, again illustrating, partially in phantom, the manner of attaching a merchandise case thereto; and

Fig. 7 is a plan view of the preferred form of blank used in forming the display rack of fibrous material illustrated in Fig. 2.

Referring now to the details of the drawings, Fig. 1 illustrates a sheet metal display rack embodying various aspects of my invention, while Fig. 2 illustrates a cardboard or fibrous sheet material display rack fabricated in accordance with aspects common to both embodiments as well as other aspects of the invention.

Both the illustrated embodiments of the invention are intended for use with merchandise display cases having re-entrant surfaces forming guideways or grooves. For purposes of illustration, razor set cases of the type disclosed in the above-mentioned Shnitzler patent are shown herein and designated by the reference character 8. These cases have, in their rear walls, re-entrant surfaces which form guideways 10, for further details of construction of these cases reference may be had to the Shnitzler patent. From a further reading of this

description, it will be apparent that my invention is not limited to use in association or combination with merchandise cases having this particular form of guideway, nor, in fact, need the guideways be formed on a common wall of the case as is herein descriptively illustrated.

While my inventive concepts are not so restricted, it is contemplated that several display cases may be attached in stacked relation to my improved display rack, as is indicated in Figs. 1 and 2. When thus stacked, a minimum of display space on a shopkeeper's counter is required, and yet a sufficient supply is provided which does not need constant replacement.

Referring more particularly to the sheet metal display rack illustrated in Figs. 1 and 3, it will be noted that this rack comprises two elongated mounting edges 12 which may be fashioned by rolling the edge of the rack material to provide rounded surfaces. In this embodiment, the edges 12 are offset from the body portion 14 of the rack by bent marginal portions 11 of the body portion.

Individual merchandise cases 8 may be attached to the display rack by slipping them downwardly along the mounting edges 12 or the edges 12 may be manually deflected inwardly to permit their insertion into the guideways 10. In any event the lowermost case 16 is brought to the extreme lower end of the display rack and positioned therat by short extensions 18, which may constitute tabs of the rack material folded inwardly to engage the undersurface of the lowermost merchandise case and thus fix its position relative to the rack. The extensions 18 are disposed to engage said lowermost case and prevent its removal from the display rack in a downward direction. At the same time, the case is positioned to provide support, in an upright sense, for the display rack and other merchandise cases which may be attached thereto. Thus, the display rack is maintained in an upright position by the lowermost merchandise case attached thereto since the rack itself is not stable, or sufficiently stable, to support itself assuredly in an upright position. In this connection, it will be noted that the vertical dimension of the rack greatly exceeds by many times the shortest of its base dimensions; the latter dimension in the present embodiment being the distance from the rear of the body portion 14 to the forwardmost portion of the extensions 18.

By referring to the showing of the second embodiment in Fig. 4, the extent by which the vertical dimension can exceed one of the base dimensions will be seen with even greater clarity. This form of my invention may be fabricated from a single blank 19 of fibrous sheet material or cardboard such as is shown in Fig. 7. Starting with the blank 19, flap 20 is first folded inwardly along indicated fold-line 21 against the body portion 22. The left-hand flap 24 may then be sheared along the solid line 23 and then be folded inwardly along the indicated fold-line 25 against the body portion 22 and the flap 20. The bottom flap 26 is then folded upwardly against the flaps 20 and 24. The end portions of the bottom flap 26 may then be bent outwardly a slight amount, along the oblique fold-lines illustrated, to form merchandise case-engaging extensions 28 (Fig. 4). The various flaps except the extensions 28 and the areas immediately adjacent thereto may then be glued or otherwise secured in their folded positions. The display rack formed in this fashion is extremely inexpensive and provides many fringe economies over conventional racks. It will be noted, however, that this rack is substantially planar so that it may be shipped and stored, before use, with a minimum of space.

In using a rack formed from the type of blank illustrated in Fig. 7, or any rack of similar configuration fabricated of sheet material which is substantially planar, its mounting side edges 30 formed by the folds along

the fold-lines 21 and 25 are bowed inwardly as illustrated in Figs. 4 and 6 and positioned for insertion into the merchandise case guideways 10. Upon release the side edges 30 will engage the grooves 10 under the influence of the resilient characteristics of the sheet material to effect securing of the case to the display rack. After attachment the lowermost case may be slid downwardly until it is positioned by the extensions 28 and resting in the fold formed thereby with the body portion 22. When so positioned, the lowermost case serves as a base member for the display rack as well as for other merchandise cases which may be attached thereto in stacked relation, as was described with respect to the embodiment shown in Fig. 1.

It will be apparent that both embodiments of my invention are uniquely supported, that is there is a mutuality of support between the case and the rack. A case combines with and provides support, in an upright sense, for either rack shown while the rack, by engagement with the case grooves 10, maintains the cases in stacked relation.

While the display rack illustrated in Fig. 2 can be fabricated of various different materials, I have found that further economies can be attained by using a cardboard construction. It would normally be assumed that a fibrous material such as cardboard which had sufficient strength to withstand the usage and abuse expected of such display racks would have, in turn, such high frictional characteristics that it would be extremely inconvenient, if not impossible, to slide merchandise cases along the mounting edges 30. We have found, however, that merchandise cases may readily be attached to the rack by bowing the edges 30 inwardly as described above. During the interval of time, normal between assembly of the rack and cases and their appearance on a retailer's counter, a permanent set may occur in the flexed cardboard which fits into the grooves 10 of the merchandise cases. After this set has occurred, the resilient characteristics of the cardboard material are greatly reduced, thus tending to reduce the force of engagement between the cases and the display rack. Such reduction in force facilitates the sliding of the cases along the display rack.

The importance of the discussion of the sliding movement of the cases along the display rack is of greater importance when it is realized that the normal manner of removing a merchandise case is to slide it upwardly until it is disengaged from the mounting edges of the display rack. In this connection, it will be noted that the first and second embodiments described are provided with enlarged portions 34, 36 respectively, on which may be imprinted advertising or other information. In the first embodiment merchandise cases may be freely moved upwardly along the mounting edges 12 as they are offset with respect to the portion 34 to which rigidity is added by the upward extension 37 of flap 24. However, the embodiment of Fig. 2 is designed to take advantage of the economies offered by a substantially planar form and its mounting edges 30 are therefore not offset in this fashion. In order to permit removal of the display cases by upward movement thereof, notches 38 and 38' are provided immediately beneath the enlarged portion 36. The notch 38' is formed by a cut-out 39 in the blank 19. These notches permit the end walls of the display case adjacent the grooves 10 to pass in front of the display rack as each individual case is being removed, as is illustrated in Fig. 5.

Having thus described my invention, what I claim as new and desire to secure by Letters Patent of the United States is:

1. The combination of an elongated rack and a detachable merchandise case, said case forming a base for said rack for supporting said rack in an upright position, said rack being formed of resilient material

and having a top, bottom and continuous parallel side mounting edges and stop means positioned adjacent the bottom, said case having opposed re-entrant vertically-extending channels therein, said mounting edges being positioned in and frictionally engaging said channels of said case and said stop means engaging the bottom portion of said case, said edges and stop means positioning said case substantially normal to said rack and adjacent the bottom thereof so that said case, when the bottom thereof is positioned on a supporting surface, 10 supports said rack in upright position.

2. The combination as set forth in claim 1 wherein said rack is formed of fibrous cardboard and said stop means comprises a flap formed integrally with and folded upwardly from the bottom of said rack.

3. The combination as set forth in claim 1 wherein

said rack is formed of fibrous cardboard and said stop comprises a tab formed integrally with the bottom of said rack, said tab extending outwardly from said rack at substantially a right angle thereto.

UNITED STATES PATENT OFFICE
CERTIFICATE OF CORRECTION

Patent No. 2,949,192

August 16, 1960

John D. Maliff

It is hereby certified that error appears in the printed specification of the above numbered patent requiring correction and that the said Letters Patent should read as corrected below.

Column 6, line 1, for "fibrous cardboard" read -- sheet metal --; same line, after "stop" insert -- means --.

Signed and sealed this 11th day of April 1961.
